Morsell & Keeney
ATTORNEYS.

UNITED STATES PATENT OFFICE.

ANDERS H. NESHEIM, OF MILWAUKEE, WISCONSIN, ASSIGNOR, BY MESNE ASSIGNMENTS, TO FEDERAL STEEL SASH COMPANY, OF WAUKESHA, WISCONSIN, A CORPORATION OF WISCONSIN.

WINDOW.

Application filed December 12, 1921. Serial No. 521,738.

To all whom it may concern:

Be it known that I, ANDERS H. NESHEIM, a citizen of the United States, and resident of Milwaukee, in the county of Milwaukee and State of Wisconsin, have invented new and useful Improvements in Windows, of which the following is a description, reference being had to the accompanying drawings, which are a part of this specification.

10 This invention relates to improvements in windows.

One of the objects of the invention is to provide a window of simple and strong construction, the frame and sash of which are 15 preferably formed of commercial or stock material welded or otherwise secured together, and which will be economical to manufacture.

A further object of the invention is to 20 provide novel means whereby the sash may be readily swung into any one of several oblique positions.

A more specific object of the invention is to provide a frame including a pair of 25 upright members having adjacent one edge thereof inturned flanges which flanges are transversely slotted preferably medially so as to provide a pair of bearings thereon, in combination with a window sash having 30 outwardly extending flanges adapted to be inserted into said slots, the window sash having transversely extending bearings, preferably in the form of an angle bar, adapted 35 to cooperate with said first mentioned bearings whereby the sash may be swung relative to the frame, the upright members adjacent their other edge, preferably also having inturned flange disposed opposite the lower portion of the first mentioned in- 40 turned flanges, thus providing stop members both at the top and bottom of the frame for the swinging sash.

A further object of the invention is to 45 provide novel means for locking the sash in open position.

A further object of the invention is to provide novel means for locking the sash in closed position, the means for locking the sash when in open and closed positions 50 preferably includes a locking bar universally pivoted to the sash which is adapted to engage a suitable keeper attached to the frame when the sash is in open position and

which is also adapted to engage another keeper when the sash is in closed position, thereby locking the sash either in open or closed position, as may be desired.

The invention consists in the novel constructions, arrangements and devices to be hereinafter described and claimed for carrying out the above stated objects and such other objects as will appear from the following description of a certain preferred embodiment illustrated in the accompanying drawings, wherein—

Fig. 1 is an elevational view of a window embodying the principles of the invention, looking from a point on the outside thereof;

Fig. 2 is an elevational view of the window shown in Fig. 1, but looking from a point on the inside thereof;

Fig. 3 is a sectional view taken on the line 3—3 of Fig. 1, the sash, however, being in open position;

Fig. 4 is a sectional view, on an enlarged scale, taken on the line 4—4 of Fig. 2; and

Fig. 5 is a sectional view, on a reduced scale, taken on the line 5—5 of Fig. 4.

Like characters of reference designate like parts in the several views.

Referring now to the drawings, the window frame includes a pair of upright members 7 secured at the bottom to a sill member 8 and at the top to a cross member having a downwardly extending flange 9^a, 85 all said members preferably being of commercial or stock material welded or otherwise secured together to form a rigid frame. The upright members 7 are provided with inturned flanges 10, which flanges have 90 transversely extending slots 11 to provide a pair of aligned bearings in the form of transversely extending shoulders 12.

The frame for the sash may be formed of any suitable commercial or stock material, 95 the sides 13, top 14, and bottom 15 thereof preferably being formed of T-shaped members welded together at the corners. The members 13 are thus provided with out-turned flanges 16 which are offset at 17 so 100 that the upper portions of the flanges 16 will be behind the respective flanges 10 of the frame members 7 and the lower portions of said flanges 16 will be in front of the respective flanges 10 when the sash is operatively positioned in the frame. The sash

frame is preferably provided with a transversely extending flange 18 which is adapted to lie on top of the shoulders 12 thus pivotally supporting the sash in the window frame. The frame members 7 are each provided with an angle bar 19 positioned with the flanges 19^a thereof inturned as clearly shown in Figs. 3 and 4 of the drawings.

It will be apparent that the sash is pivotally supported in the frame with the bottom surface of the flange 18 in engagement with the upper surfaces of the respective bearings or shoulders 12 formed on the frame. When the sash is in closed position, the upper portions of the outwardly extending flanges 16 overlap, on the inside, the upper half of the respective inturned flanges 10 of the upright frame members and the lower portions of the flanges 16 overlap, on the outside, the lower half of said respective flanges 10, thus providing a practical weatherproof construction. The upwardly extending flange of the sash cross bar 14 bears against the downwardly depending flange 9^a of the transverse frame member 9, whereby a weather proof construction is provided at the top of the window. The upper portion of the flange 10 of the upright frame members and the flange 19^a of the angle bar 19 attached to the lower portion of the frame members form stop means for the upper and lower portions of the sash when the latter is swung to its closed position.

It will thus be seen that the sash is pivotally mounted in the frame without the use of any hinges, trunnions or the like commonly employed for that purpose. The sash as a whole may be readily removed from the frame by shifting it in the direction of the arrow shown in Fig. 3, the lower portions of the outwardly extending flanges 16 readily sliding through the respective slots 11 of the upright frame members.

The means for maintaining the sash in open position preferably comprises a locking arm 20 pivoted to a member 21 by a horizontal pin 22, the member 22 itself being pivoted to a member 23 by a vertical pin 24. The member 23 is secured to the back of the window sash in any desired manner. It will thus be seen that the locking arm 20 is universally pivoted to the window sash. The bottom of the locking arm is provided with a series of notches 25 so that the locking arm, when in a position substantially at right angles to the plane of the window sash, may be brought into holding engagement with the upwardly extending flange of a keeper 26 attached to the window frame. The window frame is also provided with a keeper 27 behind which the locking arm 20 may be slipped when the arm is parallelly positioned with respect to the window sash

and the sash is in its closed position, thereby effectively locking the sash against swinging movement relative to the window frame.

I claim:

1. In combination, a frame including a pair of upright supporting members having inturned flanges, said flanges being slotted transversely intermediate the top and bottom thereof to provide a pair of bearings, a window sash having outwardly extending flanges adapted to slip into said slots, and a transversely arranged flange extending right angularly from said window sash frame at the point of engagement with said slots adapted to co-operate with said first mentioned bearings whereby said sash may be swung out of the plane of said members into an oblique position. 70

2. In combination, a frame including a pair of upright supporting members having inturned flanges, said flanges being slotted transversely intermediate the top and bottom thereof to provide a pair of bearings, and a window sash having outwardly extending flanges adapted to slip into said slots 75 and a transversely extending flange adapted to rest on said bearings whereby said sash may be swung out of the plane of said members into an oblique position. 80

3. In combination, a frame including a pair of upright supporting members having adjacent one edge inturned flanges, said flanges being slotted transversely intermediate the top and bottom thereof to provide a pair of bearings, a window sash having outwardly extending flanges adapted to slip into said slots 90 and a transversely extending right angularly arranged flange adapted to rest on said bearings whereby said sash may be swung out of the plane of said members into an oblique position. 95

100

4. In combination, a frame including a pair of upright supporting members, a pair of aligned bearings provided on said members intermediate the top and bottom thereof, a window sash having bearing means adapted to co-operate with said first mentioned bearings whereby said sash may be swung out of the plane of said members into an oblique position, a locking arm universally pivoted to said sash, means on the frame adapted to be engaged by said arm to lock the sash in any of its several oblique positions, and means on the frame adapted to be engaged by said arm to lock the sash in its closed position. 115

120

5. In combination, a frame including a pair of upright supporting members, a pair of aligned bearings provided on said members intermediate the top and bottom thereof, 130

a window sash having bearing means adapted to co-operate with said first mentioned bearings whereby said sash may be swung out of the plane of said members into an oblique position, a notched locking arm universally pivoted to said sash, a keeper on the frame adapted to be engaged by said arm when the latter is at substantially right angles to the plane of the sash, and a keeper on the frame adapted to be engaged by said arm when the latter is substantially parallel to the plane of the sash and the sash is in its closed position, for the purpose specified. In testimony whereof, I affix my signature.

ANDERS H. NESHEIM.
